UNITED STATES PATENT OFFICE.

FRANK O. CROSS, OF KINGMAN, KANSAS.

TAG OR CHECK RETAINER.

No. 824,911.

Specification of Letters Patent.

Patented July 3, 1906.

Application filed April 10, 1905. Serial No. 254,661.

To all whom it may concern:

Be it known that I, FRANK O. CROSS, a citizen of the United States, residing at Kingman, in the county of Kingman and State of Kansas, have invented certain new and useful Improvements in Tag or Check Retainers, of which the following is a specification.

My invention relates to tag and check retainers or holders of that type suitable for attachment to boxes, crates, &c., which are to be returned to the shipper, and my object is to produce a device of this character which will reliably retain or hold the check or tag from accidental displacement and yet permit it to be easily and quickly removed and replaced by a new one.

A further object is to produce a retainer of simple, strong, durable, and inexpensive construction and which can be secured easily and quickly to the boxes or crates.

To these ends the invention consists in certain novel and peculiar features of construction and organization, as hereinafter described and claimed, and in order that it may be fully understood reference is to be had to the accompanying drawings, in which—

Figure 1 is a perspective view of a portion of a box equipped with a tag or check retainer embodying my invention. Fig. 2 is a top view of the same.

Referring particularly to the drawings, 1 designates a sheet-metal plate slit diagonally at its corners, as at 2, so that the portion between said slits may be bent upwardly toward the front side of the body portion to provide an upwardly-disposed flange 3, the end portions being likewise bent inwardly toward the front side of the body portion to provide inwardly-disposed hooks 4. Stamped out of the flanges 4 are tongues 5, which occupy the plane of and project from the ends of the body portion and are secured by nails, screws, or rivets 6 to the box or crate A. In its upper edge near one corner the plate is recessed, as at 7, and to the right of said recess the plate is bowed outwardly from the box or crate A, as at 8, so as to provide an intervening pocket.

9 indicates the tag or check of stiff paper or cardboard, corresponding in form to and of slightly-less diameter than plate 1, so as to be slipped down into the retainer, its lower edge being embraced by flange 3, and its ends by flanges 4, said tag or check being broken away in Fig. 1 to expose the recess 7 behind it.

The clamping device for preventing the tag or check from creeping upward and out of the retainer, as shown in Figs. 1 and 2, is made from a spring-rod, the same comprising a depending end portion 10, soldered, as at 11, on the flange 4 most remote from recess 7, a substantially horizontal portion 12 to bear against the front side of the tag or check near its upper edge, the oblique arched portion 13, extending from portion 12 rearward so as to overlie the plate and tag, and the terminal 14 to fit into the pocket provided between the bowed portion 8 of the plate and the box or crate.

The tag is adapted to contain the name and address of the original consignor and the name and address of the consignee. When the latter is ready to reship the box or crate, he prepares a new tag addressed to the original shipper and containing any other matter desired, or the original tag may contain on its back the address of the original shipper, so that all that is necessary for the reshipper to do is to remove the tag, reverse it, and resecure it in the retainer, it being understood that the recess 7 is simply provided to render it more convenient to remove the tag when desired. It will also be understood that preliminary to such action the operator grasps the clamp and springs it upward until the hook is disengaged from the pocket, its natural resiliency disposing it forward of the tag to permit the latter to be easily slipped in or out of the retainer.

Having thus described the invention, what I claim as new, and desire to secure by Letters Patent, is—

A tag or check retainer comprising a plate provided with retaining-flanges on its front side to receive the tag or check and having a forwardly-bowed portion at its upper edge, and a clamping-arm adapted to bear against the front face of the tag or check and having one end secured to one of the retaining-flanges of the plate and the other end engaged in the cavity presented by the forwardly-bowed portion.

In testimony whereof I affix my signature in the presence of two witnesses.

FRANK O. CROSS.
